(57) **CLAIM**

The ornamental design for a laundry basket, as shown and described.

DESCRIPTION

FIG. 1 is a top and front perspective view of a first embodiment of the new design for a laundry basket;

FIG. 2 is a bottom and rear perspective view thereof;

FIG. 3 is an enlarged right side view thereof; left side view being identical;

FIG. 4 is a front view thereof; rear view being identical;

FIG. 5 is a top view thereof; and

FIG. 6 is a bottom view thereof;

FIG. 7 is a top and front perspective view of a second embodiment of the new design for a laundry basket;

FIG. 8 is a bottom and rear perspective view thereof;

FIG. 9 is an enlarged right side view thereof; left side view being identical;

FIG. 10 is a front view thereof; rear view being identical;

FIG. 11 is a top view thereof; and,

FIG. 12 is a bottom view thereof.

The white parts and the broken lines delineating them form no part of the claimed design.

1 Claim, 10 Drawing Sheets
